(57) **CLAIM**

The ornamental design for a container cover with seal as shown and described.

DESCRIPTION

FIG. 1 is a perspective view showing a front and top view of the container cover with seal of the present invention.

FIG. 2 is a front elevation view thereof.

FIG. 3 is a back elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is a cross-sectional view taken through line 8-8 seen in FIG. 2; and,

FIG. 9 is a perspective view showing a front and bottom view thereof.

1 Claim, 5 Drawing Sheets
